WASHING MACHINE WRINGER RELEASE

Edward R. H. Britton and Paul R. Thillard,
Locust Valley, N. Y.

Application December 17, 1936, Serial No. 116,307

8 Claims. (Cl. 68—22)

This invention relates to the releasing of the pressure on wringer rolls or the like and is more particularly concerned with a novel manner of effecting this release of pressure.

Wringer, such as used in connection with washing machines, have heretofore been provided with so-called quick-releases for quickly relieving the pressure between the rolls, but requiring positive, quick, and intelligent action on the part of an operative. One primary purpose of such quick releases is to render safer the use of pressure rolls by the ordinary person, and to provide a means for quickly releasing the pressure, if the fingers or clothing of the person should be caught between the rolls. Records will show, however, that many serious accidents have happened in using such devices, even though the pressure rolls have been provided with various types of releases. In a moment of emergency, a person usually acts by instinct and impulse and not as the result of clear and logical thought. Consequently, if a wringer release requires the exercise of a positive and intelligent act by the operative to release the pressure on the rolls, its purpose is largely defeated.

One object of this invention is to provide apparatus for quickly and positively releasing the pressure on pressure rolls by the involuntary act of an operative.

Another object is the provision of apparatus for releasing the pressure on the rolls by the pressure of a person's body against the apparatus.

A further object is the provision of a wringer release which can be manually operated and is also capable of being operated by pressing the body against a washing machine associated therewith.

Further objects and advantages will be in part explained and in part apparent from the following description of one embodiment of our invention illustrated in the accompanying drawings, in which

Fig. 1 is a side elevation of a combined washing machine and wringer provided with one form of our invention for releasing the pressure on the wringer rolls.

Fig. 2 is a horizontal sectional view taken on about the line 2—2 of Fig. 1.

Fig. 3 is a vertical sectional view of a detail of the apparatus on an enlarged scale, and taken on the line 3—3 of Fig. 2.

Fig. 4 is a detail horizontal sectional view taken on the line 4—4 of Fig. 3.

Fig. 5 is a vertical sectional view of another de-

tail shown on an enlarged scale and taken on the line 5—5 of Fig. 2.

Fig. 6 is a view similar to Fig. 5 but taken on the line 6—6 of Fig. 2, at a point opposite the wringer support.

Fig. 7 is a vertical sectional view taken on the line 7—7 of Fig. 6.

In the drawings, numeral 10 indicates generally a washing machine which may be of any conventional or other suitable construction, provided with a side wall 11. A wringer 12 is associated with the washing machine 10 and may be supported thereby in a suitable manner such as by the post 13 fixed to the washing machine. The wringer rollers may be driven by a shaft in the post 13, through a gear box 14, or in any other suitable manner as is well understood in the art. Preferably, the wringer is supported in such a manner that it may be pivoted about the post 13 as an axis into a number of different positions with respect to the washing machine 10.

The invention is not concerned with the particular construction of the washing machine 10 and the wringer 12, except as they affect the operation of the wringer release, and the principle of the invention may be applied to washing machines and wringers connected in any other suitable manner, or to wringers alone.

An annular member or ring 15 is preferably mounted on the washing machine near the upper portion thereof in such a manner that it projects out from the side of the washing machine and may be moved inward toward the washing machine by the application of a force in any direction. The inward movement of this ring 15 is then transmitted to the wringer 12 to quickly release the pressure on the wringer rolls.

In the embodiment of the invention illustrated, the ring 15 is substantially U-shaped in cross section, with its open side extending inwardly toward the washing machine. As best shown in Figs. 5, 6, and 7, the wall 11 is preferably provided with a circumferential groove 17 arranged to cooperate with, and at times to receive the annular member 15. This ring 15 is shown supported in groove 17 at five positions around the washing machine, one point of support being directly opposite the wringer supporting post 13. At this point of support, a member 18 is fixed to the wall 11 of the washing machine in some manner, as by bolts 19. Extending outward from the wall 11, the member 18 is provided with a hollow cylinder portion 20 adapted to receive the plunger 21, which is fixed to ring 15. Some resilient means such as a coil spring 22, or the like,

is employed to urge the ring outward, away from the groove 17. The cylinder portion 20 of the member 18 is provided with an opening slightly elongated in a direction circumferentially of the washing machine 10 to allow some lateral play for the plunger 21 for the purpose described below.

As many other points of support for the ring may be employed as desired. At these other points of support, the ring 15 is provided with plungers 23 cooperating in telescoping relation with the members 24 and urged apart by the springs 25. The cylinder members 24 are provided on their inner portions with smooth surfaces 26, adapted to slide circumferentially in the groove 17. Preferably the coil springs 22 and 25 are of uniform size in order to maintain the ring 15 spaced evenly from the wall 11 of the washing machine 10 under normal conditions.

Adjacent the wringer supporting post 13, a bifurcated member 27, having a pair of arms 28 and 29, is attached to the ring 15, as by bolts 30. The arms 28 and 29 are fixed to wings 31 and 32 by means of the bolts 33. Wings 31 and 32 are integral with a lower collar 34, surrounding the wringer supporting post 13. The collar 34 preferably has an internal diameter somewhat larger than the post 13, and under normal conditions is spaced uniformly therefrom. This lower collar 34 may be slidingly supported on the annular bracket member 35, which is fixed to the post 13 in some suitable manner in order to limit downward movement of collar 34. The upper surface of the collar 34 is provided at regular intervals with small sockets 36, adapted to receive the balls 37. An upper collar 38 is also mounted on the post 13 directly above the lower collar 34, and is provided with sockets 39 corresponding to sockets 36 to receive the upper portions of the balls 37. Collar 37 fits rather snugly on the post 13 and is provided with a vertically extending groove adapted to cooperate with the fixed key 40, fixed to or formed on the wringer supporting post 13. An upper annular surface is also provided on the upper collar 38 to support the roller 45 or rounded lower end 41 of the rod 42.

It will thus be seen that the lower collar 34 is capable of substantial movement radially of the post 13 in any direction, and is also capable of being rotated about the post 13. The collar 38, on the other hand, is capable of movement only in a vertical direction, being restrained against rotation and tipping by the key 40, and fitting the post 13 tightly enough to be restrained against movement laterally or radially thereof.

Rod 42 may be extended up through the gear box 14 in any suitable manner and is adapted to be moved longitudinally therethrough. At its upper end the rod 42 is pivotally attached, as by pin 43, to a crank arm 44, which in turn is pivotally supported on the fixed bracket 45. A rod 46 is pivotally connected to the other end of crank arm 44 and may be arranged in any suitable manner to trip a latch or other release, thus releasing the pressure on the wringer rolls.

One form of release is illustrated, although it is to be understood that any conventional or other suitable arrangement may be employed. The upper cross bar 47 of the wringer 12, provided with a spring 48 for applying pressure against the roller journals may be hinged at one end 49. Under normal operating conditions, the other end of bar 47 is held in contact with the main part of the wringer by means of a latch 50, pivoted on the main part of the wringer at 51 and engaging a catch 52 on the bar 47. Inward move-

ment of the rod 46 thus moves the latch 50 inward and allows the whole upper part 47 of the wringer 12 to fly up, releasing the pressure on the wringer rolls.

In the operation of this apparatus, the ring 15 is supported at a point opposite the wringer post 13 in such a way that it cannot be moved circumferentially of the washing machine 10, but can be moved inwardly against the washing machine. This is accomplished by attaching the cylinder member 18 to the wall 11. If pressure is applied on the ring 15 at this point however, the bifurcated member 27 is allowed to move in the same direction by the telescoping action of the plunger 21 and cylinder 20. At the other points of support, the supporting members for the ring are adapted to slide around the wall of the washing machine, and the first point of support mentioned above acts as a pivot. In the event of pressure being applied at any of these other points, the bifurcated member will therefore be moved in some direction radially of the supporting post 13.

Thus pressure against the ring 15 in any direction will move the bifurcated member 27 and also the lower collar 34 in a direction radially of the post 13. As any such movement of the collar 34 occurs, the balls 37 are rolled out of their sockets 36 and/or 39, or tend to roll out of their sockets by reason of the movement of the lower collar 34 relative to the upper collar 38. The rolling of the balls out of their sockets thus forces collars 34 and 38 apart and since collar 34 is prevented from moving downward, serves to raise the collar 38 and the rod 42. Upward movement of the rod 42 is then translated by crank arm 44 into lateral movement of the rod 46 inward towards the wringer to trip the latch 50 and release the pressure on the wringer rolls.

If the wringer is not pivotally mounted on the post 13 it will not be necessary, of course, to arrange the rod 42 for contact with more than one part of the collar 38. It will be apparent that the release of the latch 50 may be adjusted to respond to greater or smaller pressures as desired. The lengths of the individual arms of crank arm 44 may be so proportioned as to obtain the effect desired.

One important advantage of this invention is that an operator may release the wringer rolls by body pressure against the washing machine 10. This is distinctly advantageous as compared with a release which can only be operated by hand, especially in the event that both hands become caught in the wringer rolls at the same time. The release action is also designed to be effected by an involuntary movement of a person whose hands are caught in the wringer rolls. In such an emergency the operator should not have to spend valuable time thinking about how to release the pressure, nor should any other positive intelligent act be required. The involuntary reaction of a person whose fingers are caught is to try to pull them out of the rollers. As this is attempted, the body is necessarily pressed against the washing machine and, in accordance with this invention, the release is effected automatically.

It will be apparent that many modifications of this invention may be made without departing from the spirit thereof.

The terms and expressions which we have employed are used as terms of description and not of limitation, and we have no intention, in the use of such terms and expressions, of excluding

any equivalents of the features shown and described or portions thereof, but recognize that various modifications are possible with the scope of the invention claimed.

5 We claim:

1. In a combined washing machine and wringer, a latch for normally maintaining the rolls of said wringer under pressure, a substantially annular member surrounding said washing machine, and means operable by moving said member for releasing said latch and thereby the pressure on said wringer rolls.

10 2. In a combined washing machine and wringer, a latch for normally maintaining the rolls of said wringer under pressure, a substantially annular member surrounding said washing machine, and mechanical means actuated by movement of said member in any direction laterally of said washing machine for releasing said

20 latch.

3. In a combined washing machine and wringer, a latch for normally maintaining the rolls of said wringer under pressure, a substantially annular member surrounding the upper portion of the washing machine and projecting beyond the outer portion thereof, and means for releasing said latch upon movement of said member relative to said washing machine.

4. In apparatus of the character described a washing machine, a wringer pivotally supported by said machine, a latch for normally maintaining pressure on the rolls of said wringer, and means movably mounted on said washing machine independently of said wringer operable to

release said latch in any position of the wringer with respect to said machine.

5 5. In apparatus of the character described a washing machine, a wringer pivotally supported by said machine, a latch for normally maintaining pressure on the rolls of said wringer, means for releasing said latch, and a member surrounding said washing machine below the wringer for actuating said means to release said latch when any portion of the member is pressed 10 inward toward said washing machine.

6. In a combined washing machine and wringer, a pair of wringer rolls, means normally holding said rolls together under pressure, means for releasing said holding means, and a movable 15 member surrounding at least a portion of said washing machine below said rolls arranged to actuate said releasing means.

7. In a combined washing machine and wringer, a pair of wringer rolls, a washing tub, a latch normally serving to hold said rolls together under pressure, and a member movably supported by and surrounding at least a portion of said tub for releasing said latch.

8. Washing apparatus comprising a washing tub, a pair of wringer rolls associated therewith and pivotally mounted with respect to said tub, means normally holding said rolls together under pressure, means for releasing said holding means, and a member movably supported by and surrounding at least a portion of said tub for actuating said releasing means.

EDWARD R. H. BRITTON.
